UNITED STATES PATENT OFFICE.

DAVID YOUNG PRESTON, JR., OF DUNFIELD, DUNDEE, SCOTLAND.

COMBINATION TOY.

1,247,003.

Specification of Letters Patent. Patented Nov. 20, 1917.

Application filed December 13, 1916. Serial No. 136,595.

To all whom it may concern:

Be it known that I, DAVID YOUNG PRESTON, Jr., citizen of Great Britain, and resident of Kimberley Place, Downfield, Dundee, in the county of Forfar, Scotland, have invented certain new and useful Improvements in Connection with an Improved Combination Toy, of which the following is a specification.

10 This invention relates to toys of the kind in which two articles are combined in one.

According to this invention the toy consists of a spade or fork or similar implement having a hollow shaft or slidable sleeve 15 which is adapted to contain the beam of a pair of scales, when the scales are in the closed position. When the scales are open they are supported from the shaft of the implement. When the scales are closed the 20 arms, which support the scale pans, turn upward and form the handle.

The following description and accompanying drawings show manners of carrying out the invention.

25 Referring to the drawings:—

Figure I is a front elevation of the toy, part in section, showing the handle closed and the scales out of operation.

Fig. II is a front elevation of the toy, part 30 in section, showing the scales in the operable position.

Fig. III is a side view of Fig. II.

Fig. IV is a plan of Fig. II.

Fig. V is a front elevation of a modified 25 form of the invention.

Fig. VI is a side view of the modification showing the scales open.

Fig. VII is a side view of Fig. VI.

Fig. VIII is a plan of Fig. VI.

40 In Figs. I, II, III and IV the blade 1 of the spade is provided with a socket 2 into which fits the hollow shaft 3. Within the shaft is located a slidable plug 4, to which two arms 5 and 6, which when open form the beam of the scales, are pivoted at 7. To either end of the beam are pivoted, at 8 and 9, two curved arms 10 and 11, to which are pivoted, at 12 and 13, two scale pans 14 and 15. These scale pans are supported beneath, 45 when open, by two cylindrical tubes 16 and 17, one of which, 17, is of less diameter than the other and which fits within the other when the scales are closed, so as to form a spade handle. The plug 4 is provided with 50 a spring catch 18, to retain the plug in posi-

tion when the scales are in use. A finger 20 is fitted on the pivot 9 to indicate when the beam is level, the lower end of the finger acting as a stop to prevent the arms 5 and 6 of the beam turning downward below the 60 horizontal; the lower edges of the arms being cut and turned inward to engage the stop.

When the scales are closed the scale pans 14 and 15 lie within the space inclosed by 65 the arms 10 and 11 and the tube 17 fits within the tube 16 so as to form the handle of the spade. To open the scales the handle is drawn upward until the catch 18 is clear of the tube 3, whereupon the portions 5 and 70 6 of the beam can be opened outward to allow the arms 10 and 11 to hang downward, in which position the pans are in position for use. The blade of the spade may be of 75 wood or sheet metal and the tube 3 may be removable from the socket 2 and be secured by friction or a spring catch.

In the modification shown in Figs. V, VI, VII and VIII the socket 2 and plug 4 are made in one and form a shaft 21 to the blade 80 1, over which slides a tube 22. The arms of the beam 5 and 6 are pivoted directly to the shaft, so that when the tube is slid downward the beam can open, which allows the arms 10 and 11 to hang downward. The 85 arms 10 and 11 in this modification are formed as the two halves of a longitudinally divided shaft to the lower ends of which are attached the two halves 23 and 24 of a longitudinally divided crutch handle. The scale 90 pans in this modification are formed of flat disks and fold up into recesses 25 and 26 cut in the arms 10 and 11 when out of use. The blade of the spade together with the socket may be formed of wood, so also may the 95 handle and arms 10 and 11.

When the toy as shown in Figs. I to IV is in use the blade may be detached from the rest of the device and used as a shovel, the stem of the device being thrust into the sand, 100 soil or other supporting material to retain the scales in an operable position.

What I claim is:

1. A combination toy consisting of an implement; a shaft secured to said implement; 105 a slidable sleeve mounted on said shaft; a folding beam adapted to be inclosed by said sleeve when in the closed position and to be supported by said shaft when in the open position; arms carrying scale pans pivoted to 110

- said beam and adapted to fold up and form the handle of the implement when in the closed position.
2. A combination toy consisting of an implement; a shaft secured to said implement; a slide member supported by said shaft member; a folding beam connected to one of said members so as to be operatively supported by the shaft member when the slide member is in one adjustment and adapted to be collapsed to form a prolongation of the shaft member when the slide member is in another adjustment; and arms carrying scale pans pivoted to said arms, said arms being capable of being folded up and held in the folded position to form a handle by the slide member.
3. A combination toy consisting of an implement; a shaft member secured to said implement; a slide member supported by said shaft member; a folding beam connected to one of said members so as to be operatively supported by the shaft member when the slide member is in one adjustment and adapted to be collapsed to form a prolongation of the shaft member when the slide member is in another adjustment.
4. A combination toy consisting of an implement; a shaft member secured to said implement; a slide member supported by said shaft member; a folding beam connected to one of said members so as to be operatively supported by the shaft member when the slide member is in one adjustment and adapted to be collapsed to form a prolongation of the shaft member when the slide member is in another adjustment; and arms carrying scale pans pivoted to said beam and adapted to fold up and form the handle of the implement when the folding beam is collapsed.
5. A combination toy consisting of an implement; a shaft member secured to said implement; a slide member supported by said shaft member; a folding beam connected to one of said members so as to be operatively supported by the shaft member when the slide member is in one adjustment and adapted to be collapsed to form a prolongation of the shaft member when the slide member is in another adjustment; and arms pivoted to said beam and scale pans pivoted to said arms so arranged that the arms and scale pans may be folded in close to the folding beam in position to be held thus folded in when the folding beam is collapsed.
6. A combination toy consisting of an implement; a shaft member secured to said implement; a slide member supported by said shaft member; a folding beam connected to one of said members so as to be operatively supported by the shaft member when the slide member is in one adjustment and adapted to be collapsed to form a prolongation of the shaft member when the slide member is in another adjustment; and arms carrying scale pans pivoted to said arms, said arms being capable of being folded up and held in the folded position to form a handle by the adjustment of the slide member to the position second mentioned.

Signed at Dundee, in the county of Forfar, Scotland, this 22nd day of Novr. A. D. 1916.

DAVID YOUNG PRESTON, JR.
